DESIGN FOR A BLOUSE

Herman F. Eisenberg, New York, N. Y.

Application August 11, 1939, Serial No. 86,611

Term of patent 3½ years

To all whom it may concern:

Be it known that I, Herman F. Eisenberg, a citizen of the United States of America, residing in New York city, in the Borough of Manhattan, county and State of New York, have invented a new, original, and ornamental Design for a Blouse, of which the following is a specification, reference being had to the accompanying drawing, forming part thereof, wherein

Figure 1 is a front view of a blouse showing my new design.

Figure 2 is a rear view of a blouse shown in Figure 1.

The characteristic feature of my design resides in the combination on the blouse disclosed, of the specific arrangement of the contrastingly colored edging on the epaulettes, collar, front button panel, front pleats and cuffs, as shown.

I claim:

The ornamental design for a blouse, substantially as shown, and described.

HERMAN F. EISENBERG.
